UNITED STATES PATENT OFFICE

134,253

DESIGN FOR A HURRICANE LAMP

Samuel L. Gerson, Bridgeton, N. J.

Application August 25, 1942, Serial No. 108,025

Term of patent 7 years

To all whom it may concern:

Be it known that I, Samuel L. Gerson, a citizen of the United States, residing in Bridgeton, Cumberland County, New Jersey, have invented a new, original, and ornamental Design for a Hurricane Lamp, of which the following is a specification, reference being had to the accompanying drawing, forming a part thereof, in which:

Fig. 1 is a side elevational view of a hurricane lamp showing my new design; and

Fig. 2 is a top plan view of the lamp.

I claim:

The ornamental design for a hurricane lamp, as shown.

SAMUEL L. GERSON.
